RAYMOND W. BURNS, OF POUGHKEEPSIE, NEW YORK.

END-CLAMPING DEVICE.

Application filed July 1, 1926. Serial No. 119,844.

It is common in the art of wood clamping where a plurality of clamps are arranged in parallel relation to provide some clamping means for engaging the end edges of such 5 work as a door or other frame-like structure at the same time, and the present invention relates to devices of that sort.

The objects of the invention are to secure an end clamping device the clamps of which 10 are capable of being elevated or moved up out of the way to permit ready access to the main clamps for inserting the work; to mount the end-clamps, for this purpose, upon means supported at the rear of the 15 main clamps or at their ends away from the operator so as to swing up and down; to utilize for this purpose the hold-down rods of the main clamps, or rods adapted to carry means for pressing down on the work being 20 clamped; to enable the end-clamps at the same time to be adjustable and also removable; to enable squaring means to be applied and cooperate with the end-clamping 25 means, and to obtain other advantages and results as may be brought out by the following description.

Referring to the accompanying drawings, in which like characters of reference indicate the same parts throughout the several views, 30 Figure 1 is a plan of a series of bar clamps of a clamp carrier, my improved end-clamping means being shown applied thereto in connection with squaring means;

Figure 2 is a section across the main 35 clamps, looking toward their front ends and taken on line 2—2, Fig. 1;

Figure 3 is an end view with the clamp carrier rods in section on line 3—3, Fig. 1;

Figure 4 is a perspective view looking 40 down upon the outer end of the main clamp to which the squaring means is attached, from its inner or opposite end;

Figure 5 is a perspective view of the outer 45 end of one of the other main clamps and its associated parts, looking down upon the same from its outer end;

Figure 6 is a perspective view of the adjustable jaw of one of the main clamps, and

50 Figure 7 is a fragmentary perspective view of parts of the squaring means.

In the specific embodiment of the invention shown in said drawings, 1, 2 and 3 indicate bar clamps of one of the transverse 55 series of clamps of a clamp carrier, although it will be understood that the present invention

is applicable to any plurality of clamps for engaging the side edges of a piece of work and that such clamps may be supported in proper relation to each other in any well-known manner varying from simply setting them upon a work-bench or the like to mounting them as one of the transverse series of a clamp carrier as I have shown. Said clamps may furthermore be of any ordinary and well-known construction providing at one end, which is the outer end in a clamp carrier, a head 4 with a fixed jaw 5 and providing nearer the other end an adjustable jaw 6 adapted to be slid upon side bars 7, 8 by suitable means such as a draw bar 9 between said side bars and having apertures 10 to engage said jaw and adapted to be moved longitudinally by a handled nut 11 upon a screw 12 with which said draw bar 9 terminates at the head of the clamp. At the other or inner end of the clamp is a connection between the side bars 7, 8, and in the particular clamp shown this connection takes the form of a spanner foot 13 adapted to engage spaced cross-rods 14, 14 such as are mounted at their opposite ends in links of the endless conveyor chains of a clamp carrier (not shown). Pivotal 60ly mounted in said spanner foot is a member 15 providing at its forward end a seat or socket 16 for a removable rod 17 and having at its rear end 18 a spring 19 to normally swing said socket and rod upward. This rod 17 projects forwardly above the clamp upon which it is mounted and is adapted to be pressed down at its outer end by the operator and held parallel to the clamp by a hook 20 upon the head 4. Such a rod 17 has been used heretofore for carrying means 65 for engaging thin work to hold it down in place and prevent it springing or bulging upwardly from the pressure upon its edges, and to this extent the clamp as thus far described is well-known and thought to need no further description.

The end-clamps of my invention extend transversely of the main clamps 1, 2 and 3, above the same, and have their bars 21 mounted upon the hold-down rods 17, one end of each bar carrying an adjustable downwardly projecting jaw 22 which can be slid quickly into any desired position, and at its other end a jaw 23 which is adapted to be moved toward the work by a screw 24. According to my invention the bars 21 of the end-clamps extend beneath the hold-down 70 75 80 85 90 95 100 105 110

rods 17 of the main clamps and are supported thereon so that whenever said hold-down rods are released from their catches 20 and thrown upward by their springs 19 to afford access to the main clamps for putting the work therein, the said end-clamps are also carried upward out of the way with said hold-down rods. Preferably the bars 21 of the end-clamps are supported by the hold-down rods 17 so as to permit adjustment of the end-clamps longitudinally of the hold-down rods and also enable the hold-down rods to slide with their main clamps longitudinally of the end-clamps, which I have shown accomplished by slides on the hold-down rods each comprising a block 25 having an upper transverse aperture 26 to receive a hold-down rod 17 and a lower transverse aperture 27 at right angles to the upper one (see Figure 5) to slidably receive an end-clamp bar 21, the block having at its upper part a set screw 28 to clamp it in position upon the hold-down rod. By this arrangement the main clamps are all adjustable with respect to one another to enable them to be moved nearer together or further apart to accommodate different pieces of work, and the end-clamps are similarly adjustable with respect to each other. Furthermore, upon releasing the hooks 20 the rods 17 are all swung upward, as shown in Figure 3, and carry with them the end clamps out of the way of the operator in taking out or putting in work. Obviously the end clamps may be mounted upon any suitable means supported at the rear ends of the main clamps so as to swing up and down, other than the hold-down rods shown, and may be made slidably in any suitable way other than by the slides shown, the particular construction shown being only an illustrative one of many that could be employed.

In applying the squaring means which I have shown in the drawings, an outside one of the main clamps, as 1, is provided upon the outside edges of its table or work-receiving surface with a longitudinally extending bar 29 riveted or otherwise suitably secured to the clamp with its inside edge forming a shoulder to engage the work being clamped the jaw 23 of the end-clamps bearing against the opposite edge of the bar. Another bar 30 similar to the bar 29 is arranged edgewise against the jaws 5 of the heads 4 of the main clamps and secured in right angular relation to the bar 29 by being riveted to a corner bracing plate 31 which is also riveted to the outer end of the bar 29 on the clamp 1. This corner plate 31 is most conveniently placed under the bars 29 and 30, upon the table or work-receiving surface of the clamp 1, and, to properly level up the rest of said bars for this, a spacing strip 32 is put between the bar 29 and the clamp to which it is riveted, and a spacing strip 33 is riveted to

the bottom of the bar 30 to rest upon the tables or work-receiving surfaces of the main clamps 2 and 3, this spacing strip 33 projecting beyond its bar 30, as at 34, so that the work will lie upon it as well as upon the corner plate 31. For the same reason the adjustable jaws 6 of the main clamps have each an angle 35 riveted by one flange to the face of the jaw so that its other flange lies slidably upon the work table or surface of the clamp and receives the marginal portion of the work and supports it at the same height as the opposite spacing strip projection 34 and corner plate 31.

It will be understood that the squaring means thus described does not interfere in any way with sliding of the main clamps 2 and 3 with respect to main clamp 1, the bar 30 and spacing strip 33 being attached only to clamp 1, through the corner plate 31 and bar 28, and being slidably free from clamps 2 and 3. To retain said bar 30 in place against the work tables of the main clamps, their stationary jaws 5 are each provided with an angle 36 riveted by one flange to the face of the jaw so that its other flange overlies the bar 30 as a guide, and to retain said bar 30 edgewise against the faces of said stationary jaws of the main clamps the work table of the clamp farthest from the one having the corner plate 31 is provided with a guide 37 consisting of a piece of flat steel similar to that of which the various spacing strips which have been described are made, said guide being arranged transversely of the clamp and close to the bar 30 so that the latter cannot move edgewise away from the face of the jaw 5.

While it is very useful in many cases to employ the squaring means with improved end clamps, obviously it is not necessary to do so and the end clamps can be used without any squaring means, in which case the guide 37 and angles 35 and 36 on the jaws are dispensed with. When it is desired to remove the end clamps from the main clamps, as for work in which they are not needed, their supporting rods may be removed with them or said supporting rods may remain on the main clamps to receive the usual pressure shoes (not shown) and serve in the ordinary capacity of hold-down rods. Many other variations may be made in the use of my improvements, and many modifications in the structure of parts and of the clamps to which they are applied, without departing from the spirit and scope of the invention, and therefore I do not desire to be understood as limiting myself except as required by the following claims when construed in the light of the prior art.

Having thus described the invention, what I claim is:

1. The combination with a plurality of

main clamps adapted to engage the side edges of a piece of work, and rods on said main clamps adapted to swing each toward and away from the work-receiving surface of its clamp, of an end-clamp mounted on said rods.

2. The combination with a plurality of main clamps adapted to engage the side edges of a piece of work, and rods on said main clamps adapted to swing each toward and away from the work-receiving surface of its clamp, of an end-clamp having its bar mounted on said rods.

3. The combination with a plurality of main clamps adapted to engage the side edges of a piece of work, and rods on said main clamps adapted to swing each toward and away from the work-receiving surface of its clamp, of an end-clamp having its bar 20 slidably mounted on said rods.

4. The combination with a plurality of main clamps adapted to engage the side edges of a piece of work, and rods on said main clamps adapted to swing each toward and away from the work-receiving surface of its clamp, of an end-clamp having its bar 25 mounted on said rods so as to move longitudinally thereof.

5. The combination with a plurality of main clamps adapted to engage the side edges of a piece of work and rods on said main clamps adapted to swing each toward and away from the work-receiving surface of its clamp of an end clamp having its bar 35 mounted on said rods so as to move transversely thereof.

6. The combination with a plurality of main clamps adapted to engage the side edges of a piece of work, and rods on said main clamps adapted to swing each toward and away from the work-receiving surface of its clamp, of an end-clamp having its bar 40 mounted on said rods so as to move both longitudinally and transversely thereof.

45 7. The combination with a plurality of main clamps adapted to engage the side edges of a piece of work and adjustable to work of different lengths, and rods on said main clamps adapted to swing each toward and away from the work-receiving surface of its clamp, of an end-clamp mounted on 50 said rods so as to permit sliding adjustment of the main clamps.

55 8. The combination with a plurality of main clamps adapted to engage the side edges of a piece of work, and rods on said main clamps adapted to swing each toward and away from the work-receiving surface of its clamp, of an end-clamp having its bar 60 mounted on said rods so as to permit sliding upon it in adjusting the main clamps.

9. The combination with a plurality of main clamps adapted to engage the side edges of a piece of work, and rods on said 65 main clamps adapted to swing each toward

and away from the work-receiving surface of its clamp, of an end-clamp having its bar mounted on said rods so as to move longitudinally thereof, and means for preventing such longitudinal movement. 70

10. The combination with a plurality of main clamps adapted to engage the side edges of a piece of work, rods on said main clamps adapted to swing each toward and away from the work-receiving surface of its 75 clamp, and slides on said rods each having a seat transverse to its rod, of an end-clamp having its bar slidably held in said transverse seats.

11. The combination with a plurality of 80 main clamps adapted to engage the side edges of a piece of work, rods on said main clamps adapted to swing each toward and away from the work-receiving surface of its clamp, and slides on said rods apertured 85 to receive the same and each having another aperture transverse to its rod, of an end-clamp having its bar slidably mounted in said transverse apertures.

12. The combination with a plurality of 90 main clamps adapted to engage the side edges of a piece of work, and rods on said main clamps adapted to swing each toward and away from the work-receiving surface of its clamp, of an end-clamp mounted on 95 said rods, and means for holding said rods and end-clamps swung away from the work-receiving surfaces of the clamps.

13. The combination with a plurality of 100 main clamps adapted to engage the side edges of a piece of work, and rods on said main clamps adapted to swing each toward and away from the work-receiving surface of its clamp, of an end-clamp mounted on 105 said rods, and means normally holding said rods and end-clamps swung away from the work-receiving surfaces of the clamps.

14. The combination with a plurality of main clamps adapted to engage the side edges of a piece of work, and rods on said main clamps adapted to swing each toward and away from the work-receiving surface of its clamp, of an end-clamp mounted on 110 said rods, means normally holding said rods and end-clamp swung away from the work-receiving surfaces of the clamps, and means preventing such swinging-away and holding the end-clamp in position to engage the work. 115

15. The combination with a plurality of 120 main clamps adapted to engage the side edges of a piece of work, and rods on said main clamps adapted to swing each toward and away from the work-receiving surface of its clamp, of an end-clamp having its bar 125 slidably mounted on said rods, means for locking said bar against sliding on said rods, and means normally holding said rods and end-clamp swung away from the work-receiving surfaces of the clamps. 130

16. The combination with a plurality of main clamps having jaws for the side edges of a piece of work, of a bar secured to one of said clamps to engage an end edge of the piece of work, and another bar secured to said first-mentioned bar in right angular relation thereto and lying contiguous to the faces of one set of jaws of the clamps to engage a side edge of the piece of work. 65
17. The combination with a plurality of main clamps having jaws for the side edges of a piece of work, of a bar secured to one of said clamps to engage an end edge of the piece of work, and another bar secured to said first-mentioned bar in right angular relation thereto and lying contiguous to the faces of one set of jaws of the clamps in slidable relation to other than the one having the said longitudinal bar. 70
18. The combination with a plurality of main clamps having jaws for the side edges of a piece of work, of a bar secured to one of said clamps to engage an end edge of the piece of work, another bar secured to said first-mentioned bar in right angular relation thereto and lying contiguous to the faces of one set of jaws of the clamps, and means for holding said transverse bar slidably in place with respect to said jaws. 75
19. The combination with a plurality of main clamps having jaws for the side edges of a piece of work, of a bar secured longitudinally upon the work-receiving surface of one of said clamps to engage an end edge of the piece of work, and another bar secured to the said longitudinal bar in right angular relation thereto and lying contiguous to the faces of one set of jaws of the clamps to engage a side edge of the piece of work. 80
20. The combination with a plurality of main clamps having jaws for the side edges of a piece of work, of a bar secured longitudinally upon the work-receiving surface of one of said clamps to engage an end edge of the piece of work, and another bar secured to the same longitudinal bar in right angular relation thereto and lying contiguous to the faces of one set of jaws of the clamps in slidable relation to other than the one having the said longitudinal bar. 85
21. The combination of a plurality of main clamps, two bars in rigid permanent right angular relation to each other, one of said bars lying against the faces of the stationary jaws of said main clamps and adapted to be clamped between the side edge of a piece of work and said stationary jaws and the other bar lying parallel to said main clamps, and end clamps adapted to clamp one end of the piece of work against the last-mentioned bar. 90
22. The combination with a plurality of main clamps having jaws for the side edges of a piece of work, of a bar secured longitudinally upon the work-receiving surface of one of said clamps to engage an end edge of the piece of work, another bar secured to the said longitudinal bar in right angular relation thereto and lying contiguous to the faces of one set of jaws of the clamps, and means for holding said transverse bar slidably in place with respect to said jaws. 95
23. The combination with a plurality of main clamps having jaws for the side edges of a piece of work, of a bar in parallel relation to said clamps to engage the end edge of the piece of work, a bar extending transversely of the work-receiving surfaces of the clamps contiguous to the faces of one set of their jaws and secured to the said longitudinal bar in right angular relation thereto, and means upon one of the jaws contiguous to the transverse bar for holding said bar slidably in place with respect to the work-receiving surfaces of the clamps. 100
24. The combination set forth in claim 17 in which said means is an angle upon the face of one of the jaws. 105
25. The combination with a plurality of main clamps having jaws for the side edges of a piece of work, of a bar in parallel relation to said clamps to engage the end edge of the piece of work, a bar extending transversely of the work-receiving surfaces of the clamps contiguous to the faces of one set of their jaws and secured to the said longitudinal bar in right angular relation thereto, and means upon a clamp for holding said transverse bar slidably in place with respect to its contiguous jaws. 110
26. The combination set forth in claim 25 in which said means is a stop projecting from the work-receiving surface of a clamp. 115
27. The combination with a plurality of main clamps having jaws for the side edges of a piece of work, of a bar secured longitudinally upon the work-receiving surface of one of said clamps to engage the end edge of the piece of work, a bar extending transversely of the work-receiving surfaces of the clamps contiguous to the faces of one set of their jaws, a member beneath the adjacent ends of said bars across the angle between them and holding them in right angular relation, spacing strips beneath said bars at a distance from said member, and spacing means upon jaws of the main clamps opposite the spacing strip for the transverse bar. 120

RAYMOND W. BURNS.
